COMBINED ASH TRAY AND HOLDER FOR A DRINKING GLASS OR THE LIKE

Joseph N. Amigone, Buffalo, N. Y.

Application September 5, 1957, Serial No. 47,617

Term of patent 7 years

(Cl. D85—2)

FIG. 1

FIG. 2

Des. 183,784

PAGE 2

FIG. 3

FIG. 4

FIG. 5

Fig. 1 is a side elevational view of a combined ash tray and holder for a drinking glass or the like showing my new design;

Fig. 2 is an end elevational view thereof;

Fig. 3 is an opposite end elevational view thereof;

Fig. 4 is a top plan view thereof, with certain parts broken away; and

Fig. 5 is a top perspective view thereof.

The broken line showing of a glass of Fig. 1 is for illustrative purposes only.

I claim:

The ornamental design for a combined ash tray and holder for a drinking glass or the like, substantially as shown and described.
